Primary Examiner — Bridget L Eland

(57) **CLAIM**

The ornamental design for a multi-function printer, substantially as shown and described.

DESCRIPTION

FIG. 1 is a top-right-front perspective view of the design for the multi-function printer;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines immediately adjacent the shaded areas represent the bounds of the claimed design while all other broken lines are directed to environment and are for illustrative purposes only; the broken lines form no part of the claimed design.
